UNITED STATES PATENT OFFICE.

GEORGE F. BASON, OF BROOKLYN, NEW YORK.

PORTABLE LAMP.

1,403,378.

Specification of Letters Patent. Patented Jan. 10, 1922.

Application filed April 8, 1920. Serial No. 372,493.

To all whom it may concern:

Be it known that I, GEORGE F. BASON, a citizen of the United States, and a resident of the city of New York, borough of Brooklyn, in the county of Kings and State of New York, have invented a new and Improved Portable Lamp, of which the following is a full, clear, and exact description.

The present invention relates to new and useful improvements in lamps, and it pertains more particularly to lamps of the portable type.

It is one of the objects of the invention to provide a lamp which is adapted to be secured to the back of the hand of an operator of motor vehicles in such a manner that when the operator projects his hand from the vehicle to indicate his next contemplated movement, a signal will be given to the drivers of following cars.

It is a further object of the present invention to so construct a lamp of this character that the same may be used for other purposes, such, for example, as a trouble light around the car, a parking lamp, or an inside lamp, and to this end a suitable bracket adapted to enclose the lamp and support the same at various points about the car, is provided.

It is a further object of the present invention to so construct a lamp that it may have a plurality of glasses of different colors, one of which may be clear for use as a trouble lamp, the other being colored red for use as a signal.

With the above and other objects in view, reference is had to the accompanying drawings, in which

Figure 1 is a perspective view of a lamp constructed and arranged in accordance with the present invention, and showing its method of attachment to the hand of an operator, the hand being shown in dotted lines;

Fig. 2 is a view partially in vertical section and partially in elevation, of the lamp;

Fig. 3 is a view in elevation of the lamp with its supporting bracket attached, and

Fig. 4 is a perspective view of the supporting bracket.

Referring more particularly to the drawings, the reference character 5 designates the lamp housing which is preferably circular in form, and leading into the lamp housing is a tubular member 6. The tubular member 6 is adapted to receive the fitting 7

of an incandescent lamp 8, and the fitting 9 of a suitable source of current supply 10, by means of which the incandescent lamp is supplied with current. The tubular member 6 is provided with an inner double bayonet slot 11, by means of which the lamp is secured in place, and an outer double bayonet slot 12, by means of which the fitting 9 is retained in place.

The lamp housing 5 is provided at diametrically opposite points with bayonet slots 15, and adapted to be received within the bayonet slots 15 are pins 16, said pins being carried by a sleeve or the like 17, adapted to be received within the lamp housing 5. This sleeve 17 forms the means for supporting a glass 18, which is preferably red, and is adapted to close one side of the housing 5. The opposite open side of the housing 5 is adapted to be closed by means of a clear glass 19 carried by a hood 20. The hood 20 is provided with a reduced portion 21 adapted to frictionally engage the lamp housing 5, the reduced portion 21 forming a shoulder 22 against which the glass 19 is adapted to be retained.

To provide for retaining the glass 19 in position against the shoulder 22, a resilient wire 23 is provided and the ends of this wire 23 project through an opening 24 in the hood 20. The outer edge 25 of the hood 20 is preferably curved in order that it may conform to the general shape of the back of the hand, and to provide for its attachment to the hand, straps 26 and 27 are secured at diametrically opposite points to the hood 20, the straps 27 being provided with a buckle 28 by means of which the lamp is secured in position.

Rigidly carried by the lamp housing 5, is a lug 29, and said lug has two right-angular projections 30 which provide an intervening space 31, the purpose of which will be hereinafter described.

The device as thus described is adapted to be strapped upon the back of the hand as illustrated in Fig. 1, and when in this position, it will be seen that if the operator projects his hand from the car, a red light will be projected through the glass 18 in such a manner to be clearly readable by occupants of a following car. When the device is in this position, it will be seen that the light passing through the clear glass 19 will be projected against the back of the hand and said light will not be visible.

- To provide for supporting the lamp about the car in order that the light may be projected upon the various parts upon which it is desired to operate, a bracket is employed.
- 5 The bracket consists of a piece of resilient wire bent intermediate of its ends as at 40, to provide two parallel arms 41. Each of these parallel arms 41 is provided with a substantially right-angularly disposed curved portion 42, and these curved portions 42 are adapted to embrace the lamp housing 5 behind the pins 16, as more clearly shown in Fig. 3. The arms 41 are angularly disposed with respect to each other, and slidably 15 thereover in such a manner as to contract said arms 41, is a collar 42', which through its movement expands or contracts the diameter of the two curved arms 41 and causes them to either grip or release the lamp housing 5.

After forming the two curved portions 42, the strands of wire are twisted and rigidly secured together as at 45, throughout a portion of their length, and said strands are 25 then separated as at 46, and terminate in angularly disposed arms 47, each of which is provided with a curved extremity 48. This curved extremity 48 may be suitably covered with a tubular rubber body or any 30 other means to prevent its scratching or marring the part with which it is engaged to support the lamp.

As shown in Fig. 3, when the lamp housing is positioned within the curved portions 35 42, the base of the twisted portion 45 is adapted to be received within the space 31 between the right-angular projections 30 of the lug 29. By this construction, it will be seen that the lamp may be supported at any 40 convenient position in order to project a

light through the clear glass 19 when it is desired to work on any portion of the car.

It will be further noted that the present invention provides a lamp which may be used both as a signal to indicate the contemplated movement on the part of the driver of a car, and as a trouble light when it is necessary to repair or work upon the car.

Claims:

1. A signal lamp comprising a housing having oppositely disposed open walls, a colored glass secured in one of said open walls, a plain glass mounted in the other of said open walls and oppositely disposed with respect to said colored glass, said housing having a portion so formed as to fit upon the operator's hand, said portion being adjacent one of said open walls so that with the lamp in position upon the operator's hand one of said glasses is obscured, and securing means for securing said housing upon the operator's hand.

2. A device of the character described comprising a housing having a pair of oppositely disposed open walls, a colored glass secured in one of said open walls, a plain glass mounted in the other of said open walls and oppositely disposed with respect to said colored glass, said housing being so formed that it may be fitted against the operator's hand in such manner as to cause the operator's hand to obscure one of said glasses, means for securing said housing upon the operator's hand, and a bracket for temporarily mounting said housing upon a suitable mechanical support so as to support said housing independently of the operator's hand.

GEO. F. BASON.
